United States Patent Office

Des. 202,197
Patented Sept. 7, 1965

202,197
DESK

Ronald H. Beckman, New York, N.Y., assignor to Herman Miller, Inc., Zeeland, Mich., a corporation of Michigan

Filed Nov. 27, 1964, Ser. No. 82,823

Term of patent 14 years

(Cl. D33—7)

FIG. 1.

FIG. 2.

FIG. 3.

FIG. 4.

FIG. 5.

FIG. 1 is a front perspective view of a desk showing my design in closed position;

FIG. 2 is a front elevational view;

FIG. 3 is an end elevational view;

FIG. 4 is a rear elevational view; and

FIG. 5 is a front perspective view of the desk with the pivotal flap in raised position.

The end of the desk not shown is a mirror image of the end shown.

I claim:

The ornamental design for a desk, substantially as shown and described.
